Primary Examiner — T Chase Nelson*Assistant Examiner* — Mary Claire Ramirez(74) *Attorney, Agent, or Firm* — Daniel Hammond(57) **CLAIM**

The ornamental design for a camera enclosure, as shown and described.

DESCRIPTION

FIG. 1 is a bottom perspective view of a camera enclosure showing the new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines in the drawings illustrate portions of the camera enclosure that form no part of the claimed design.
